Attorney, Agent, or Firm—Walter H. Schneider

[57] CLAIM

The ornamental design for a combined food container and bottle, as shown.

DESCRIPTION

FIG. 1 is a perspective view of a combined food container and bottle showing my new design;

FIG. 2 is a top plan view;

FIG. 3 is an end elevational view;

FIG. 4 is a side elevational view;

FIG. 5 is a medial, longitudinal sectional view;

FIG. 6 is an exploded perspective view;

FIG. 7 is a top view of the container with the cover and bottle removed;

FIG. 8 is a top view of the bottle;

FIG. 9 is a side view of the bottle;

FIG. 10 is an end view of the bottle;

FIG. 11 is an end view of the other end of the bottle; and

FIG. 12 is a bottom view of the bottle.
